UNITED STATES PATENT OFFICE

172,963

WALL CONTAINER FOR ROLL PAPER

John G. Glenn, Ontario, Calif., assignor of one-half to Jack E. Jones, Ontario, Calif.

Application June 8, 1953, Serial No. 25,377

Term of patent 3½ years

(Cl. D4—3)

To all whom it may concern:

Be it known that I, John G. Glenn, a citizen of the United States, residing at Ontario, in the county of San Bernardino and State of California, have invented a new, original, and ornamental Design for a Wall Container for Roll Paper, of which the following is a specification, reference being had to the accompanying drawing, forming part thereof.

Fig. 1 is a front view in perspective of a wall container for roll paper, in closed position, showing my new design;

Fig. 2 is a plan view thereof; and

Fig. 3 is a front view in perspective of the wall container in open position.

I claim:

The ornamental design for a wall container for roll paper, as shown.
